UNITED STATES PATENT OFFICE.

ORSON G. PECK, OF YATES, MICHIGAN.

SAW-HANDLE.

SPECIFICATION forming part of Letters Patent No. 598,293, dated February 1, 1898.

Application filed June 21, 1897. Serial No. 641,694. (No model.)

To all whom it may concern:

Be it known that I, ORSON G. PECK, a citizen of the United States, residing at Yates, in the county of Manistee and State of Michigan, have invented certain new and useful Improvements in Saw-Handles; and I do hereby declare the following to be a full, clear, and exact description of the invention, such as will enable others skilled in the art to which it appertains to make and use the same.

My invention relates to a novel form of saw-handle for crosscut-saws; and the object is to provide a simple, effective, and durable device of this class.

15 To this end the novelty consists in the construction, combination, and arrangement of the same, as will be hereinafter more fully described, and particularly pointed out in the claim.

20 In the accompanying drawings the same reference characters indicate the same parts of the invention.

Figure 1 is a side elevation of my improved saw-handle. Fig. 2 is an end view of the saw and handle. Fig. 3 is a vertical section of the same. Fig. 4 is a similar view taken at a right angle to the preceding view. Fig 5 is a horizontal section on the line 4 4 of Fig. 2.

1 represents the handle, of which 2 is the 25 hand-grip and 3 the cylindrical socket which receives the saw-blade 4. The cylindrical socket 3 is provided with a longitudinal slot 5, which receives the parallel sheet-metal plates 6 and 7. The outer parallel edges 6' 6' and 7' 7', respectively, are turned over the angular edges of the sections 8 and 9 of the cylindrical socket. 10 represents a transverse bolt fixed in the outer end of said socket and at a right angle to the slot 5, and its outer 30 ends are provided with fixed burs or diamond-shaped washers 11 11, the body of which conforms to the semicircular shape of the sections 8 and 9, and their pointed ends 12 12 overlap and secure the flanged edges 6' and 7' of the plates 6 and 7 to securely clamp them in place on the socket. 13 represents a longitudinal slot formed in the inner end of the socket in line with the bolt 10 and at a right angle to the slot 5. 14 represents a transverse 35 bolt engaging said slot, and its fixed head 15

is also semicircular in form to encompass half of the socket, and its diamond-shaped ends 16 16 overlap the flanged edges 6' 6' of the plate 6 and firmly clamp it to the section 8. 17 represents a correspondingly-shaped 55 washer mounted on the threaded end of the bolt 14, and it is provided with a plane face 18, which forms a bearing for the thumb-nut 19. The pointed ends 17' 17' of this washer overlap the flanged edges 7' 7' of the plate 7, 60 so as to clamp them to the section 9. The saw-blade 4 is formed with a V-shaped notch 20 on its lower edge, which engages the fixed bolt 10, and its upper edge is also provided with a corresponding notch 21 to receive the 65 adjustable bolt 14.

To detach the blade from the handle, the thumb-nut 19 is loosened and the bolt 14 pushed up to the inner end of the slot 13. This releases the notch 21, and the saw-blade 70 may then be pushed up to release the bottom notch 20 from the fixed bolt 10, so that the blade may be withdrawn from between the plates 6 and 7 in the slot 5. By reversing the order of procedure the blade is again fixed in 75 place, and when the notch 20 engages the bolt 10 and the bolt 14 is forced down into the notch 21 the handle is brought to a right angle to the blade.

Although I have specifically described the 80 construction and relative arrangement of the several elements of my invention, I do not desire to be confined to the same, as such changes or modifications may be made as clearly fall within the scope of my invention 85 without departing from the spirit thereof.

Having thus fully described my invention, what I claim as new and useful, and desire to secure by Letters Patent of the United States, is—

The handle 1 formed with the cylindrical socket 3, comprising the semicylindrical sections 8 and 9, the parallel plates 6 and 7 having their parallel flanged edges 6' and 7' turned over the parallel edges of the sections 8 and 9 respectively, the fixed bolt 10 extending transversely through said sections and plates and provided with the diamond-shaped washers 11 11, having outer ends overlapping the flanged edges of said plates the adjust- 90 95 100

able bolt 14, extending through said sections and plates, and provided with a fixed head 15 having its outer pointed ends 16 16 overlapping the flanged edges 6' 6' of the plate 6, 5 the correspondingly-shaped washer 17 mounted on said bolt 14 and provided with a plane face 18 and having its pointed ends 17' 17' overlapping the flanged edges 7' 7' of the plate 7, and the thumb-nut 19 adapted to secure

said washer 17 in place, substantially as shown and described.

In testimony whereof I affix my signature in presence of two witnesses.

ORSON G. PECK.
